UNITED STATES PATENT OFFICE.

GEORGE C. GRAHAM, OF WATERTOWN, MASSACHUSETTS.

WASHING MACHINE.

Application filed October 20, 1924. Serial No. 744,562.

To all whom it may concern:

Be it known that I, GEORGE C. GRAHAM, a citizen of the United States, and resident of Watertown, county of Middlesex, State 5 of Massachusetts, have invented an Improvement in Washing Machines, of which the following description, in connection with the accompanying drawing, is a specification, like characters on the drawing representing like parts.

This invention relates to washing machines of that type which comprise an expandable and contractible chamber adapted to contain the clothes to be washed and communicating with a receptacle containing washing fluid, and means to alternately expand and contract said chamber whereby during the expanding movement of the chamber the cleansing fluid will be drawn 15 thereinto and the clothes will become saturated therewith while during the contracting movement of said chamber the cleansing fluid will be squeezed out of the clothes and forced back into the receptacle again.

In performing the washing operation with a machine of this type it is sufficient if during the contracting movement of the chamber the clothes be subjected to a moderate pressure only. In a machine in which 20 the clothes-receiving chamber has a fixed volume when it is fully expanded, the amount which it is necessary to contract the chamber in order to develop this moderate pressure for squeezing the suds or washing 25 fluid out of the clothes will depend upon the amount of clothes in the chamber. If the chamber is well filled with clothes then a relatively small contracting movement will answer the purpose whereas if there is a 30 small amount of clothes in the chamber then a greater contracting movement will be necessary to squeeze the washing fluid out of the clothes.

One of the objects of my invention is to 45 provide a washing machine which is constructed so that the proper pressure will be established automatically during the contracting movement of the chamber regardless of the amount of the clothes therein. In 50 other words, one object of my invention is to provide a novel washing machine in which the contracting movement of the chamber will be automatically terminated as soon as the required pressure is reached.

Some washing machines of this type are 55 also constructed so that the clothes-receiving

ing chamber can be contracted under a high pressure sufficient to compress or squeeze substantially all of the cleansing fluid from the clothes and bring them to a semi-dried 60 condition, this being the equivalent to wringing the clothes in the ordinary washing operation.

Another object of my invention is to provide a novel construction whereby the machine may be adjusted to operate under either the moderate pressure required for washing or the higher pressure desirable for drying the clothes and whereby the desired pressure, whether high or low, will be automatically established regardless of the amount of clothes in the clothes-receiving chamber.

A machine embodying my invention is, therefore, in a sense automatic in its action 75 in that all that is required of the operator is to place the clothes in the clothes-receiving chamber and set the machine in operation, said machine operating automatically to establish the desired pressure for washing or for drying the clothes regardless of the amount of clothes in the chamber.

In order to give an understanding of the invention I have illustrated in the drawings 85 a selected embodiment thereof which will now be described after which the novel features will be pointed out in the appended claims.

Fig. 1 is a sectional view illustrating a 90 machine embodying my invention;

Fig. 2 is an enlarged sectional view through the by-pass relief valve;

Fig. 3 is a sectional view showing a different embodiment of the invention.

The expandable and contractible clothes-receiving chamber in which the clothes are received is located within a shell 1 which is herein shown as divided to form the two sections 2 and 3. Extending across the shell is a flexible diaphragm 4 which forms with the shell section 2 the clothes-receiving compartment 5 in which the clothes 6 to be washed are placed. Said diaphragm 4 also forms with the shell section 3 a chamber 7, which will be hereinafter again referred to. 100

The clothes-receiving compartment 5 has communicating therewith a pipe connection 8 which leads to a tank 9 adapted to contain suds or other washing water or cleansing fluid. The communication between the pipe 8 and the clothes-receiving chamber 105 110 5 is through an intermediate chamber 10

which is formed within a hood member 11 which is secured to the exterior of the shell 1, said shell having the perforations 12 therein which form a communication between the chambers 5 and 10. When the chamber 5 is expanded, therefore, the cleansing fluid will be drawn into said chamber through the pipe 10, chamber 11 and perforations 12.

10 As stated above the sections 2 and 3 of the casing are separable to permit the clothes 6 to be placed in the chamber 5 or removed therefrom and the sections may be clamped together in any suitable way 15 as by means of clamps 13. It is necessary to maintain a tight joint at the division line between the sections 2 and 3 and this is herein accomplished by clamping the peripheral edge of the diaphragm 4 to a flange 14 formed on the shell section 3 by means of a clamping ring 15 and by providing the shell section 2 with a flange 16 which is clamped against the ring 15 by the clamps 13, a suitable gasket ring 20 being interposed between the flange 16 and clamping ring 15 to make a tight joint.

This construction provides a clothes-receiving chamber 5 having one fixed wall formed by the shell section 2 and a movable wall formed by the diaphragm 4 and the expansion and contraction of the chamber 5 is secured by moving the diaphragm 4 up and down. This movement of the diaphragm may be obtained in various ways 30 without departing from my invention.

The construction herein shown for this purpose is a pump comprising a cylinder 17 having a piston 18 operating therein and one end of which is connected to the chamber 7 by means of a pipe connection 40 19. The chamber 7, pipe connection and cylinder are filled with water or some other relatively non-compressible fluid so that when the piston 18 moves downwardly the fluid will be forced into the chamber 7 thus moving the diaphragm 4 up and contracting the clothes-receiving chamber 5 while when the piston 18 moves upwardly water will be withdrawn from the chamber 7 into the cylinder 17 and the diaphragm 4 will be moved downwardly thus expanding the clothes-receiving chamber 5.

The piston 18 is shown as reciprocated by means of a crank disk 20 which is rotated from a motor 21 through suitable reduction gear indicated generally at 22. This means of expanding and contracting the clothes-receiving chamber is substantially the same as that shown in my co-pending application, Serial No. 743,306, filed October 13th, 1924.

As stated above in performing the washing operation it is sufficient if at each down stroke of the piston 18 the diaphragm 4 65 is moved upwardly to such a point as to

place the clothes under moderate pressure. The exact point at which this occurs will, of course, depend upon the amount of clothes 6 in the chamber 5. If the chamber is well filled with clothes then a relatively small upward movement of the diaphragm 4 will develop the required pressure while if there are only a few clothes in the chamber a greater upward movement will be required for this purpose.

70 My present invention provides automatic means for terminating the upward movement of the diaphragm 4 when the desired pressure is reached regardless of the amount of clothes in the chamber. This is accomplished by employing a by-pass with a relief valve arranged to open when the desired pressure has been reached so that if this pressure is reached before the piston 18 reaches the lower end of its stroke then 80 during the further movement of the piston water will be forced through the by-pass. The device also includes means for returning the water to the system again during the up-stroke of the piston so as to maintain the cylinder 7 and the pipe connections full of water.

75 The drawings show a simple construction which accomplishes this result.

80 30 indicates an auxiliary tank divided by 90 a partition 24 into two compartments 25 and 26. The compartment 25 is connected to the pipe 19 by a by-pass pipe connection 27. Said partition has therein a spring-pressed relief valve 28 which opens upwardly and also a spring-actuated inlet valve 29 which opens downwardly. The valve 28 is acted on by a spring 30 which will hold the valve shut until a predetermined pressure has been reached.

100 It will be noted that because of the connections illustrated the pressure in the chamber 25 will be the same as that in the chamber 7 and, therefore, the same as that to which the diaphragm 4 is subjected. When the pump is operating to force fluid into the chamber 7 and thereby contract the clothes-receiving chamber the clothes will be subjected to an increasing pressure and when this pressure reaches a predetermined point 110 the valve 28 will open against the action of the spring 30 thereby allowing the water or other fluid to flow through the by-pass connection into the auxiliary tank 26. This opening of the valve 28 will thus limit the pressure to which the wall 4 is subjected and will thus limit the upward movement of the wall and the consequent contracting movement of the clothes-receiving chamber. The spring 30 will be so adjusted as to limit 115 the contracting movement of the clothes-receiving chamber when the proper pressure has been reached for the washing operation.

120 During the reverse action of the pump the water will be drawn out of the chamber 7 130

and the diaphragm will move downwardly thus expanding the chamber 5. If the diaphragm moves downwardly to a point where it comes in contact with the shell 3 before the piston 18 has completed its upward movement then during the final movement of the piston the valve 29 will open and water will flow from the reserve chamber 26 into the chamber 25 and thence into the system.

The exact point at which the relief valve 28 will open during the down stroke of the piston 18 will, of course, be dependent on the amount of clothes in the chamber. If the chamber is well filled with clothes the required pressure will be reached at an earlier point in the down stroke of the piston 18 than if the chamber is only partially filled with clothes but in either event the relief valve 30 automatically takes care of the matter so that under all conditions only the required pressure against the diaphragm 4 will be developed during each down stroke of the piston.

A machine of this type is adapted to bring the clothes to a semi-dried condition by subjecting the diaphragm 4 to a relatively high pressure which will result in squeezing the clothes under its high pressure between the diaphragm and the fixed casing 2.

I have provided herein means whereby when the clothes are to be dried the relief valve may be held to its seat under a relatively high pressure. In the construction shown in Figs. 1 and 2 this is accomplished by providing a second spring 31 for acting on the valve 28 which is much heavier than the spring 30 and by providing means whereby said spring 31 may be rendered operative or inoperative.

32 indicates a follower which is slidably mounted on the valve stem 33 and which forms a backing for the springs. This follower is connected by links 34 to a lever 35 which is pivoted at 36 and is adapted to be moved up and down.

The spring 31 is of such dimensions that when the lever is in its raised position shown in Fig. 1 the follower will be separated from said spring as shown in Fig. 2. The spring 30, however, has such dimensions that it engages the follower at all times and, therefore, when the lever is raised as shown in Figs. 1 and 2 the heavy spring 31 is inactive and the valve 28 is held to its seat by the lighter spring 30 only. If, however, the lever is moved downwardly into the dotted line position so as to bring the follower against the spring 31 as shown by dotted lines Fig. 2 then said heavy spring comes into action and will resist the opening movement of the valve 28. Therefore, when the lever is swung downwardly to bring the heavy spring 31 into action the relief valve will not be opened until suf-

ficient pressure has been developed in the chambers 7 and 25 to overcome the heavy spring, which pressure will be sufficient to bring the clothes to a semi-dried condition.

The lever 35 can be retained in either its raised or lowered position by means of a clamping screw 37 operating in a slot in a bracket arm 38.

With this construction the operation of washing the clothes consists simply in placing the clothes in the chamber 5 and raising the lever 35 to the full line position Fig. 1 so as to leave the heavy spring 31 inactive. When the machine is started in operation the washing action will be performed as above described and at each down stroke of the piston the relief valve 28 will open when the pressure against the diaphragm reaches the predetermined point which is suitable for the washing operation and during any further downward movement of the piston 18 the surplus water will be forced through the relief valve into the chamber 26. The volume of the cylinder 17 will preferably have such a relation to the size of the casing 1 that at each down stroke of the piston 18 the required pressure against the diaphragm 4 will be developed before the piston reaches the lower end of its stroke so that the relief valve will be opened and some water will be forced into the chamber 27 while during the final end of the upstroke of the piston 18 the suction valve 29 will be opened to allow water to return to the system.

When the washing operation has been completed and it is desired to bring the clothes to a semi-dried condition, the lever 35 will be moved downwardly into the dotted line position thus bringing the heavy spring 31 into action. When the parts are so adjusted then during the downward movement of the piston 18 the pressure which is developed against the diaphragm 4 will be determined by the action of the heavy spring 31 which may be such as to bring the clothes to a semi-dried condition.

The operation of the relief valve, therefore, results in subjecting the clothes to the same pressure during the washing operation and also to the desired pressure during the drying operation regardless of the amount of clothes in the chamber.

In Figs. 1 and 2 a construction is shown where both the high pressure and the low pressure are secured from the operation of the same relief valve by the use of two different springs. In Fig. 3 another construction is shown which involves the use of two relief valves 39 and 40, one of which, the valve 39, is controlled by a relatively light spring 41, and the other of which, the valve 40, is controlled by a relatively heavy spring 42. Where the two relief valves are used, the valve 39, which is controlled by the light

spring, will normally function and this is the valve which operates during the washing of the clothes.

For bringing the clothes to a semi-dried condition the valve 39 is locked to its seat and then the only relief valve which is operative is the other valve 40 which is controlled by the heavy spring. This locking of the valve 39 to its seat may be provided for by employing a lever 43 pivoted at 44 and having an arm 45 adapted to engage the stem 46 of the valve 39 when the lever is moved into the dotted line position Fig. 3.

15 During the washing operation the lever will be held in its inoperative position in full lines and the relief valve 39 will function. When the washing is completed and it is desired to bring the clothes to the semi-dried condition the lever 43 is placed in the dotted line position thus locking the valve 39 to its seat and when this condition obtains the diaphragm 4 will, during the down stroke of the piston 18, be subjected to relatively high pressure which is determined by the strength of the spring 42 controlling the relief valve 40.

16 The lever 43 may be held in either of its positions by means of a locking pin 47 adapted to enter apertures in a bracket arm 48.

In order that the machine may operate properly it is, of course, necessary that no air should be trapped in the chamber 7. Said chamber has connected to it at its upper end a pipe 49 which is controlled by a valve 50 and which leads into the receptacle 26. In starting the machine the valve 51 will be opened during the first part of the down stroke of the piston 18 and as the piston descends any air in the chamber 7 will be driven out through the pipe 49.

As soon as the air has all escaped the valve 50 will be closed and will remain closed during further operation of the machine.

In practice it may be desirable to use a cylinder and piston which at each stroke of the piston displaces a volume somewhat less than the volume of the casing 1. Under ordinary conditions a considerable portion of the volume of the chamber 5 will be occupied by the clothes being washed so that the amount of water to be displaced in carrying the diaphragm 4 from its lowest point to the point required to subject the clothes to pressure is considerably less than the total volume of the casing 1.

Where this relation between the size of the cylinder and the size of the casing 1 exists it will be necessary to use a larger volume of water between the piston 18 and the diaphragm 4 when a small amount of clothes is being washed than when a larger amount is being washed. If, for instance,

the chamber 5 is well filled with clothes then it will be sufficient to use a less volume of water between the piston 18 and the diaphragm 4 that when the piston reaches the lower end of its stroke the diaphragm will be raised to a point to place the clothes under the desired pressure. If, however, only one or two pieces are being washed then it will be necessary to raise the diaphragm 4 further in order to develop the required pressure. This can be done by introducing a larger volume of water between the piston 18 and the diaphragm and such introduction of the larger amount of water may be made by simply opening the suction valve 29 while the piston 18 is moving upwardly so that water will flow from the chamber 26 into the system. When this larger volume of water is thus introduced between the piston 18 and the diaphragm then during the down stroke of the piston the diaphragm will be raised to a greater extent depending upon the amount of water added to the system and during the upstroke of the piston the diaphragm will be moved only part way to the bottom of the casing. By thus opening the inlet valve 29 during the upstroke of the piston 18 the volume of the water between the piston and the diaphragm may be adjusted to correspond to the amount of clothes being washed.

In fact, one convenient way of operating the machine would be to open the inlet valve 29 when the piston 18 is at the bottom of the stroke and the diaphragm is at the upper limit of its movement and then to maintain the inlet valve opened while the piston moves upwardly so as to completely fill the system with water. Then when the piston moves downwardly again the relief valve will open when the desired pressure is reached thus discharging the surplus water back into the tank 26.

The inlet valve 29 may be opened in various ways for the above-described purpose. One simple device is to employ a push pin or "tickler" 55 which is so situated that by depressing the latter the inlet valve will be forced from its seat and thus opened.

If it is desired to rinse the clothes and blue them as well as wash them I propose to employ additional tanks or receptacles 51 and 52, one to contain rinsing water and the other to contain blueing water and then to shift the pipe connection 8 from one tank to another to perform the rinsing and blueing operations.

While I have illustrated herein some selected embodiments of my invention I do not wish to be limited to the constructional features shown.

I claim:

1. In a washing machine, the combination with an expandible and contractible

- chamber adapted to receive the clothes to be washed, a receptacle containing washing fluid with which said chamber communicates, means to alternately expand and contract 5 said chamber whereby during the expansion of said chamber the washing fluid is drawn into the chamber and the clothes become saturated thereby and during the contraction of the chamber the washing water is 10 squeezed from the clothes and returned to the receptacle, and means for automatically limiting the contracting movement of the chamber when the clothes are subjected to a predetermined pressure.
- 15 2. In a washing machine, the combination with an expansible and contractible chamber adapted to receive the clothes to be washed, a receptacle containing washing fluid with which said chamber communicates, means to alternately expand and contract 20 said chamber whereby during the expansion of said chamber the washing fluid is drawn into the chamber and the clothes become saturated thereby and during the contraction of the chamber the washing water is 25 squeezed from the clothes and returned to the receptacle, means for automatically limiting the contracting movement of the chamber when the clothes are subjected to a predetermined pressure, and means whereby such predetermined pressure may be varied.
- 30 3. In a washing machine, the combination with an expansible and contractible clothes-receiving chamber having a removable wall, of a receptacle containing cleansing fluid with which the chamber communicates, means to move said movable wall away from and toward the fixed wall thereby to alternately expand the clothes-receiving chamber and draw washing fluid therein and to contract said chamber and to force the washing fluid therefrom, and means automatically to limit the movement of the movable wall when a predetermined pressure has 45 been reached.
- 40 4. In a washing machine, the combination with an expansible and contractible clothes-receiving chamber having a movable wall, of a receptacle containing washing water with which said chamber communicates, a chamber filled with fluid, one side of which is formed by said movable wall, means alternately to withdraw fluid from said chamber and then to force it into the chamber under 50 pressure, whereby the movable wall is moved to expand and contract the clothes-receiving chamber and means automatically to prevent the development of excessive pressure in said chamber.
- 55 5. In a washing machine, the combination with a casing, of a movable diaphragm extending across the casing and forming with one wall thereof an expansible and contractible clothes-receiving chamber, a receptacle containing washing water with 60 which the clothes-receiving chamber communicates, a pump device for pumping fluid into the other chamber within the casing and then withdrawing fluid therefrom, whereby the clothes-receiving chamber is 70 expanded and contracted and a relief valve for relieving any excessive pressure which develops in said other chamber.
- 65 6. In a washing machine, the combination with a casing having a movable diaphragm 75 extending thereacross and dividing it into two chambers, one of which is a clothes-receiving chamber, of a receptacle containing cleansing fluid connected with said clothes-receiving chamber, a cylinder having a piston therein connected with the other chamber, said chamber and cylinder being filled with water, means for operating the piston, whereby the clothes-receiving chamber is 80 alternately expanded and contracted, and a spring-pressed relief valve for relieving any excessive pressure developed in said other chamber during the pressure stroke of the piston.
- 85 7. In a washing machine, the combination with a casing having a movable diaphragm 90 extending thereacross and dividing it into two chambers, one of which is a clothes-receiving chamber, of a receptacle containing cleansing fluid connected with said clothes-receiving chamber, a cylinder having a piston therein connected with the other chamber, said chamber and cylinder being filled with water, means for operating the piston, whereby the clothes-receiving chamber is 95 alternately expanded and contracted, an auxiliary tank, a by-pass connecting said tank with the other chamber, a suction valve and a relief valve in said by-pass connection, whereby when during the contraction of the clothes-receiving chamber the clothes are subjected to a predetermined pressure the relief valve will open and the water will be forced by the piston through the by-pass and relief valve to the auxiliary tank and during the suction stroke of the piston water will be drawn back into the system through the suction valve.
- 100 8. In a washing machine, the combination with a casing having a movable diaphragm 105 extending thereacross and dividing it into two chambers, one of which is a clothes-receiving chamber, of a receptacle containing cleansing fluid connected with said clothes-receiving chamber, a cylinder having 110 a piston therein connected with the other chamber, said chamber and cylinder being filled with water, means for operating the piston, whereby the clothes-receiving chamber is alternately expanded and contracted, an auxiliary tank, a by-pass connecting said tank to said other chamber, a suction valve and a relief valve in said by-pass, whereby when during the contraction of the clothes-receiving chamber the clothes are subjected 115 to a predetermined pressure the relief valve will open and the water will be forced by the piston through the by-pass and relief valve to the auxiliary tank and during the suction stroke of the piston water will be drawn back into the system through the suction valve.
- 120 9. In a washing machine, the combination with a casing having a movable diaphragm 125 extending thereacross and dividing it into two chambers, one of which is a clothes-receiving chamber, of a receptacle containing cleansing fluid connected with said clothes-receiving chamber, a cylinder having a piston therein connected with the other chamber, said chamber and cylinder being filled with water, means for operating the piston, whereby the clothes-receiving chamber is alternately expanded and contracted, an auxiliary tank, a by-pass connecting said tank to said other chamber, a suction valve and a relief valve in said by-pass, whereby when during the contraction of the clothes-receiving chamber the clothes are subjected 130 to a predetermined pressure the relief valve will open and the water will be forced by the piston through the by-pass and relief valve to the auxiliary tank and during the suction stroke of the piston water will be drawn back into the system through the suction valve.

to a predetermined pressure the relief valve will open and the water will be forced by the piston through the by-pass and relief valve to the auxiliary tank and during the suction stroke of the piston water will be drawn back into the system through the suction valve, and means whereby the relief valve may be adjusted to open under either a relatively light pressure or a relatively heavy pressure.

9. In a washing machine, the combination with a casing, of a movable diaphragm extending across the casing and dividing the latter into two chambers, one of which is a clothes-receiving chamber, a cylinder con-

nected to the other chamber, a piston operating in the cylinder, the space between the piston and the diaphragm being filled with water, whereby the reciprocating movement of the piston vibrates the diaphragm and thus expands and contracts the clothes-receiving chamber, a receptacle containing washing water with which said clothes-receiving chamber communicates, and means for varying the volume of the water between the piston and the diaphragm.

In testimony whereof, I have signed my name to this specification.

GEORGE C. GRAHAM.
